DESIGN FOR A PILLOW TOP OR SIMILAR ARTICLE

Anna L. Ejk, South Plainfield, N. J.

Application October 23, 1934, Serial No. 53,730

Term of patent 14 years

To all whom it may concern:

Be it known that I, Anna L. Ejk, a citizen of the United States, and a resident of South Plainfield, in the county of Middlesex, and State of New Jersey, have invented the new, original, and ornamental Design for a Pillow Top or Similar Article, of which the following is a specification, reference being had to the accompanying drawing, forming part thereof.

The figure of the drawing is a plan view of a pillow top, having no appreciable thickness, showing my design.

The design is characterized by its application to the pillow top by means of beads or representations of beads, of varying sizes and colors, the resulting design typifying a peacock.

I claim:

The ornamental design for a pillow top or similar article, as shown and described.

ANNA L. EJK.
